UNITED STATES PATENT OFFICE

DAVID HODGE, OF CENTRALIA, ILLINOIS, ASSIGNOR TO SAFETY MINING COMPANY,
OF CHICAGO, ILLINOIS, A CORPORATION OF ILLINOIS

BLASTING DEVICE

Application filed January 31, 1929, Serial No. 336,419, and in Great Britain October 5, 1928.

This invention relates to cartridges, and particularly to cartridges which are discharged by an electric current, requiring a connection to a more or less remote source of current to effect the discharge, and is herein illustrated as applied to a blasting cartridge of the type disclosed in the co-pending application of Arthur W. Helmholz and Dent Ferrell, Serial No. 169,441, filed February 19, 1927.

An object of this invention is to provide a cartridge which may be electrically discharged, but which is not subject to being accidentally discharged by accidental or inadvertent contact with current lines or terminals which may be in the neighborhood of the cartridge during storage, transportation or other handling of the cartridge prior to its placement in the drill hole ready for discharge.

Another object of the present invention is to provide a cartridge and a terminal for a current line, which cartridge and line are adapted to be inserted in the drill hole at the site of a blasting operation, the terminal being readily and detachably receivable in the cartridge to establish an electric circuit therefor.

Another object is to provide an electrically operated cartridge and current line terminal of the above described type in which the conductors leading to the electrically discharged element in the cartridge are normally provided with a low resistance shunt connection which prevents the passage of any appreciable current through said element, such as would cause discharge thereof, the parts being so constructed that the current line terminal which may be in the nature of a plug will not only establish the proper electrical connections for the circuit, but will operate to disconnect the shunt whereby the cartridge is rendered dischargeable at such times only when the terminal or plug is in inserted position, such as when the cartridge is inserted into the drill hole and connected to the plug for discharge.

Another object of the invention is to provide an improved form of current line cable, plug and cartridge construction by which the

present invention may be readily practiced, and which will make for ease and efficiency in operation and simplicity and cheapness in manufacture.

Various other objects not enumerated are contemplated in this invention, which will appear as the description proceeds of the embodiment of the invention herein given for the purpose of illustration.

The present disclosure is given merely by way of example and is not to be considered as limiting the invention in any regard, but merely as one embodiment thereof, and the scope of the invention will be determinable from an understanding of the present disclosure as an embodiment of the invention, with recognition of the advantages which the invention produces in the illustrated embodiment.

Referring to the drawings—

Figure 1A is a cross sectional view of one end of a cartridge construction embodying the present invention, and Figure 1B is a similar view of the other end of the cartridge, the entire cartridge being represented when Figure 1B is placed at the right hand end of Figure 1A.

Figure 2 is a cross sectional view of one end of a modified cartridge construction embodying the present invention.

Figure 3 is a view similar to Figure 2 showing a second modified construction embodying the present invention.

Figure 4 is an end elevation of Figure 2 as seen from the left.

Referring to the drawings, it will be noted that the present invention is disclosed as embodied in a cartridge of the type disclosed in the co-pending application above referred to, which comprises a casing of cylindrical construction having a rupturable wall at one end and containing a gaseous medium in highly compressed form, together with an electrically discharged heating element having the proper connections for establishing a circuit for discharging the cartridge.

Inasmuch as terminals are required, it is desirable to provide a higher degree of safety in assurance against accidental dis-

charge such as might occur if the terminals are accidentally brought in contact with a current line or other source of current.

In practice it has been found convenient 5 to utilize the metal casing as one of the conductors for the heating element, and where this type of cartridge is employed together with grounded electrical circuits it becomes obvious that a safety prevention assuring 10 against accidental discharge is highly desirable, as the possibility of accidental contact of a single terminal with one line of a grounded circuit is not so remote, and such contact might result in discharge of the 15 cartridge when the casing, or one conductor thereof, is grounded, as for instance by resting on a metallic car or other grounded conducting part.

The present embodiment of the invention 20 provides a shunt of low resistance, connected across the terminals of the heating element so that any accidental passage of current through the cartridge parts will be prevented from acting to discharge the heating 25 element. The cartridge further embodies means for disconnecting the above described shunt and establishing a complete circuit for discharging the heating element at the time the cartridge is connected and inserted 30 in the drill hole for discharge purposes.

Referring to the drawings, it will be noted that the present disclosure of the invention relates to a cartridge having a cylinder 10, constricted at one end at 11, with the central opening 12, and having an open end nozzle 13 at its opposite end. For closing the nozzle end a rupturable disk 14 is provided, held by means of the shear ring 15 and the discharge cap or cage 16, which is 40 screw threaded at 17 to the casing so as to present the rupturable disk in close sealing contact with the knife edge projection 18 on the end of the casing. At the opposite end a tube like element 19 is positioned 45 through the opening 12 and insulated therefrom by means of the insulation 20, 21 and 22, which tube serves in the dual capacity of an electrical conductor and an inlet tube for the gaseous medium.

50 The tube is held by means of the flange or collar 23 and the nut 24, which are insulated from the casing by means of the insulation 25 and 26, which parts constrict the insulation material and the collar 27 55 in tight bearing against the opposite ends of the collar 28, the latter being screw threaded as at 29 in the opening 12 of the casing. Screw threaded on the end of the stem 19, as at 30, and inside of the nut 24, as at 31, is the valve housing 32, having the valve stem 33 screw threaded therein, the valve stem being provided with a needle valve end 34, and key stem 35, all of such construction that the needle valve 60 65 may be presented in tight sealing relation

against the end 36 of the duct 37 provided for the introduction of gas into the cartridge.

The gas is introduced through the duct 38 in the valve housing by a suitable means 70 clamped tightly thereto, so that when the valve is moved away from its seat, gas under pressure may be forced into the cartridge, the construction permitting (upon the introduction of a sufficient amount of gas) the 75 valve to be seated for preventing escape of the gas so introduced prior to the removal of the introducing nozzle, or other means applied against the opening 38.

The above structure is substantially similar to that disclosed in the co-pending application referred to.

The valve stem is provided with suitable packing and glands, represented generally at 39, of the same construction as shown in 85 the co-pending application.

Inside the cartridge, mounted on the threaded end 40 of the stem 19, is a spring housing 41 containing the spring 42, and forming a slide mounting for the spring 90 pressed contact plate 43. Surrounding the contact plate is a supporting tube 44, preferably perforated and terminating short of the opposite end of the cartridge, as shown at 45 in Figure 1B. Positioned in the tube 95 44 is a heating element 46 of any suitable construction, but which may be of paper tube construction, having plugs 47 at its opposite ends and containing a suitable material and an electrical conducting wire 48, the latter of which is curled at its opposite ends to bear against the contact plate 43 at one end, and the rupturable disk 14 at its opposite end.

The wire passes through the casing and 105 is in association with the material contained therein so as to render the cartridge dischargeable upon the passage of sufficient current through the conducting wire.

It will be noted that one end of the heating element is in electrical contact with the casing 10 so that the casing will serve as one terminal in establishing the electrical circuit for discharging the cartridge. At the end opposite the discharge end of the cartridge an enclosed casing cap or extension 49 is provided, screw threaded as at 50, and preferably formed of the same diameter as the casing 10, so that the entire unit may be inserted into the drill hole 120 without having projections or other portions thereon which will hinder the introduction of the cartridge in the drill hole.

The casing cap 49 is provided with an inner cavity 50 and an opening or socket 125 51 leading thereto.

The cavity 50 is lined as at 52 with insulating material to assure against short-circuiting by contact of any of the valve parts previously described, which are 130

housed within the cavity. Bearing against the nut 24 is a metallic ring 53, forming a seat for the coil spring 54, the outer end of which has mounted thereon a cap 55, adapted under normal conditions to close the inner end of the opening 51. The cap 55 is larger in diameter than the opening and is adapted to bear against the annular flange 56 provided at the inner margin of the opening.

The cap 55, it will be noted, is provided with a projecting male portion 57, adapted to be received in a female portion of a plug hereinafter described. The male projection 57 is provided with a slot 58, whereby ready insertion may be accomplished while maintaining a snug fit therefor. The cap 55, when the cartridge is not connected for discharge, as when inserted in the drill hole, is urged by the spring 54 in contact with the flange 56, whereby the inner end of the socket opening 51 is closed against the entrance of dirt or moisture into the cavity 50, and further, a low resistance short-circuiting or shunt connection provided across the terminals of the heating element preventing accidental passage of current therethrough and consequent discharge thereof prior to the time that the cartridge is actually connected for discharge purposes.

The socket 51 is adapted to receive a plug which is secured as a permanent connection to the end of a current line, such as a line of the type leading to and adapted to be used at the site of the blasting operation. The current line may be of any suitable construction, but, for the purpose of this invention, is found to serve well when formed of a central conducting core 58, insulated from the core by means of the insulating sleeve 60. The cable or line so formed may, of course, be entirely encased in insulating material 61.

The plug comprises a metallic or conducting member 63, having a flared opening 64 therethrough, leading to the conduit 65 passing therethrough. The conducting portion 63 is provided with lugs 66 which cooperate with the slots 67 at the end of the casing cap 49 to form a breech lock or other suitable quickly acting and readily detachable locking connection.

The portion 63 is threaded as at 68 for receiving the securing sleeve 69, having a flanged end at 70. Inside of the sleeve 70 is the conducting element 71, having the female socket portion 72 for receiving the male projection 58 previously described. The conducting element 71 is insulated from the outer casing cap by means of insulation 72 and 73. The inner conducting core 58 of the current line or cable is permanently secured in the conducting element 71 as at 74, whereas the core is insulated from the conducting portion 63 by the insulation 65.

The outer conducting sleeve 59 enters the opening 64 of the conducting portion 63, and is in electrical contact therewith, as at 75, whereby a plug is provided which may be readily inserted into the socket for establishing electrical connections with the casing as one terminal of the heating element, and the cap 55 as the other terminal of the heating element.

Attention is directed to the fact that the plug is of such construction and size that the insulating sleeve 73 contacts the cap 55 when the plug is completely inserted, and moves it away from its short-circuiting contact with the annular flange 56 of the casing cap. This, it will appear, establishes the complete circuit for discharging the heating element upon the passage of current through the two conductors of the current line.

From the foregoing description, it will be obvious that the invention provides a cartridge which may be readily attached to the current line at the time that the cartridge is inserted in the drill hole for discharge, and that a high degree of convenience and ease of manipulation is provided in that various cartridges may be supplied and connected to a common electrical line in succession as they are used, that is to say, the terminal plug may be reused with the various cartridges in successive blasting operation, the plug being readily disconnected and reconnected to a new unused cartridge. This construction has proven to be strong and durable and with the strong breech lock connection it is found that the discharging operation does not damage the plug or its connection with the current line, consequently the spent cartridge may be readily recovered and the plug inserted in a new cartridge for a subsequent blasting operation.

In the form shown in Figure 1A it is a feature of the invention to provide the opening 64 for receiving the current line substantially at one margin thereof, or in other words, eccentric to the center, whereby the current line may enter into the cartridge near the bottom edge thereof so as to permit the current line to rest on the bottom surface of the drill hole. This feature is advantageous in assisting in closing the drill hole behind the cartridge such as by tamping, or with the use of dummies or the like, as the current line will be out of the center and always in a given position whereby allowance may be made therefor.

Referring now to Figure 3, the parts are substantially the same and accordingly will not be described again, except that the current line 100 enters the portion 163 of the plug centrally thereof, with the conducting sleeve 159 screw threaded as at 160 into the plug portion, or otherwise securely fixed thereto. Here a slightly modified form of

breech lock is provided through the instrumentality of the lugs 166 and grooves or openings 167 provided in the casing cap. This construction is clearly shown in Figure 4. In Figure 3, a modified form of plug is shown which is locked in the end of the casing cap by means of projections 266 operated by balls 267. The female conducting element 271 is provided with a screw 272 for engaging in the end of the core conductor of the circuit line. The conducting portion 263 of the plug is insulated from the female portion 271 by means of insulation 273 and 274. A nut 275 is provided at the outer end to assist in securing the end of the circuit line to the plug, which nut is screw threaded to the conducting portion 273, as at 273. An enclosed collar 277 is provided for closely engaging the inner end of the circuit line.

In operation it will be appreciated that the cartridges as filled and supplied for use will be provided with a shunt of low resistance which will prevent accidental discharge, even though accidental contact is made on the inner terminal of the circuit. The cartridge further provides greater assurance against such accidental discharge, as the inner terminal is the male projection 57, and is housed well within the casing cap at a substantial distance inwardly of the edge thereof, and in such protected position that it can only be brought in contact with an electrical line by deliberate insertion of the line into the socket opening.

The invention also provides a readily detachable connection which is reusable with the various cartridges in succession, which plug not only establishes the proper electrical connection for discharging the cartridge, but also disconnects the shunt or short-circuiting connection, which ordinarily maintains the cartridge incapable of accidental discharge.

It is obvious that various forms and modifications may be made without departing from the spirit of the present invention, and the present disclosure is not to be considered as limiting the invention in any regard. The scope of the invention is fully set forth in the appended claims.

I claim:

1. In an electrically discharged cartridge, a casing and a heating unit in said casing, said heating unit being electrically connected to said casing and to a terminal within said casing, and a detachable means, connected to a source of current, adapted to be inserted in said casing for establishing an electrical circuit with said casing and terminal, said terminal being normally in electrical contact with said casing, and adapted to be moved out of contact therewith by said detachable means.

2. In a device of the character described,

the combination of an electrically discharged cartridge having means for receiving a plug for establishing an electrical circuit therefor, a plug for said cartridge and an electrical conducting line, said line having a core of conducting material and a concentric sheath of conducting material insulated from said core, said plug being mounted on said line having independent parts insulated from each other, connected to said core and sheath respectively, said plug being adapted to be inserted and detachably held in said cartridge for establishing an electrical circuit therefor.

3. In a device of the character described, an electrical line and a plug having two terminals secured on the end of said line, an electrically discharged cartridge having two terminals, and adapted to receive said plug, said terminals being normally in contact, but capable of being moved out of contact by said plug when in inserted position.

4. In a device of the character described, the combination of a casing having an opening and a yielding cap for closing said opening and contacting said casing, an electrically discharged unit in said casing connected to said casing and cap respectively, a plug connected to a source of current adapted to be received in said opening and to establish an electrical connection with said casing and cap respectively, said plug upon movement into connected position serving to move said cap out of contact with said casing, whereby an electrical circuit is established for discharging said unit.

5. In a device of the character described, the combination of a casing having an opening and a yielding cap for closing said opening and contacting said casing, an electrically discharged unit in said casing connected to said casing and cap respectively, a plug connected to a source of current adapted to be received in said opening and to establish an electrical connection with said casing and cap respectively, said plug upon movement into connected position serving to move said cap out of contact with said casing, whereby an electrical circuit is established for discharging said unit, said cap and plug having interfitting male and female portions.

6. In a device of the character described, the combination of a cartridge adapted to be inserted in a drill hole, said cartridge having a socket and electrical terminals in said socket, a plug adapted to be received in said socket and to establish electrical connection with said terminals, a line connected to said plug, said line entering said plug substantially at one marginal edge thereof whereby said line may readily rest on the bottom of the drill hole when said cartridge and plug are in inserted position.

7. In a device of the character described,

- the combination of a line, and a plug adapted to be secured in a cartridge for establishing an electrical connection therewith, said line having concentrically arranged inner and outer conductors, insulated from each other, said plug having two conducting portions insulated from each other, said line being secured to said plug with the outside conductor in contact with the first of said portions, and the inside conductor passing through and insulated from said first portion and being secured in contact with the second of said portions.
8. A cartridge of the character described having a casing, and an electrically discharged unit in said casing, a socket in said casing having terminals for said unit, a plug connected to a source of current adapted to be received in said socket and having means for establishing an electrical connection with said terminals, said socket and plug having a breech lock connection for detachably securing said plug in place.
9. A cartridge of the character described, comprising a casing, a heating unit in said casing, means connecting said heating unit to said casing and a terminal in said casing, an opening in said casing and a spring-pressed cap closing said opening and normally maintaining said cap in contact with said casing, a cap spring establishing an electrical connection between said terminal and said cap, a plug connected to a source of current adapted to be received in said opening, having means establishing an electrical connection with said casing and cap respectively, said plug acting to move said cap out of contact with said casing when said plug is in connected position, whereby an electrical circuit is established for said cartridge, said spring maintaining an electrical connection between said cap and terminal for all positions of said cap.
10. In an electrically discharged cartridge, a casing having an electrically discharged heating unit contained therein, said casing being connected to serve as one terminal for said heating unit and a second terminal housed within said casing, a socket in said casing adapted to receive a plug, a plug connected to a source of current adapted to establish a circuit with said terminals, said plug being adapted to complete the connection by movement into position in said socket, and being capable of slight angular movement for detachably locking said plug against accidental displacement.
11. In an electrically discharged cartridge, a casing and a heating unit in said casing, said heating unit being electrically connected to said casing and to a terminal within said casing and a detachable means connected to a source of current, adapted to be inserted in said casing for establishing an electrical circuit with said casing and terminal, means normally operative to form a low resistance shunt between said casing and terminal, said means being rendered inoperative by insertion of said detachable means.
12. A blasting cartridge comprising a casing adapted to receive a charge of liquefied gas having electrically operated means for vaporizing the charge, the circuit of said means including the casing of said cartridge as one electrode and a second electrode insulated with respect to said casing, and means normally effective to provide a short circuit between said electrodes, a cap for one end of said casing and means whereby said short circuiting means is rendered ineffective upon the application of said cap to said casing.
13. A blasting cartridge having means whereby the same may be electrically activated and including two electrodes in circuit, a member detachably associated with said cartridge for conveying current to said electrodes and means whereby said electrodes are short circuited when said member is detached from said cartridge.
14. A blasting cartridge having means whereby the same may be electrically activated and including two electrodes in circuit, a member detachably associated with said cartridge for conveying current to said electrodes and means whereby said electrodes are short circuited when said member is detached from said cartridge and means associated with said member for rendering said short circuiting means ineffective when said member is attached to said cartridge.
15. A blasting cartridge having means whereby the same may be electrically activated, means for short circuiting said means, means detachably associated with said cartridge for supplying current to the first said means and means whereby said second named means is rendered ineffective by the application of said third named means to the cartridge.
16. A blasting cartridge having means whereby the same may be electrically activated, means for short circuiting said means, means detachably associated with said cartridge for supplying current to the first said means and means whereby said second named means is rendered ineffective by the application of said third named means to the cartridge, said second named means being normally effective when said third named means is detached from the cartridge.
17. A blasting cartridge comprising a casing adapted to receive a charge of liquefied gas and having electrically activated means for vaporizing said charge, said means consisting of an electric circuit including an electrode insulated from said casing and whereof the said casing constitutes the other

electrode and cooperating contact means having electrical connections with the respective electrodes and adapted to be brought into contacting relation for short circuiting said electrodes, means normally urging said contact means into contacting relation to produce and maintain a short circuit, a conductor carrying member detachably associated with said cartridge for supplying current to the circuit including the two said electrodes and means effective upon the attachment of said member to the cartridge for separating said contact means.

18. A blasting cartridge comprising a casing adapted to receive an explosive charge and having electrical means for energizing the charge, said means comprising a circuit including the said casing as one electrode and a second electrode insulated from the casing, a contact member fixed with respect to one of said electrodes and having electrical connection therewith and a second contact movable with respect to but having electrical connection with said other electrode and adapted to engage the first said contact member to provide a short circuit across said electrodes.

19. A blasting cartridge comprising a casing adapted to receive an explosive charge and having electrical means for energizing the charge, said means comprising a circuit including the said casing as one electrode and a second electrode insulated from the casing, a contact member fixed with respect to one of said electrodes and having electrical connection therewith and a second contact movable with respect to but having electrical connection with said other electrode and adapted to engage the first said contact member to provide a short circuit across said electrodes and spring means for urging said contact members into contacting relation.

20. A blasting cartridge comprising a casing adapted to receive an explosive charge and having electrical means for energizing the charge, said means comprising a circuit including the said casing as one electrode and a second electrode insulated from the casing, a contact member fixed with respect to one of said electrodes and having electrical connection therewith and a second contact movable with respect to but having electrical connection with said other electrode and adapted to engage the first said contact member to provide a short circuit across said electrodes, means for urging said contact members into contacting relation, a cap for said casing having relatively insulated electrical connections adapted to conduct current to the respective electrodes when attached to said casing and means whereby the attachment of said cap to said casing causes separation of said contact members.

21. A blasting cartridge comprising a substantially cylindrical metallic body having a gas chamber formed therein and opening at one end thereof, a pressure responsive discharge device associated with said end, the other end of said body having an open ended cylindrical pocket, a transverse wall separating said gas chamber and pocket, an electrode passing through said wall and insulated therefrom and extending on opposite sides thereof into said pocket and gas chamber respectively, a plug having relatively insulated portions adapted to be connected to the respective leads from a source of electricity, a lug and slot connection between said plug and body and means for electrically connecting a portion of said plug with said electrode.

22. An electrically energizable blasting cartridge comprising relatively insulated parts, an electrically energizable device in circuit between said parts, and a detachable plug having lug and slot connection with said cartridge, said plug having relatively insulated portions adapted to make electrical contact with the respective portions of said cartridge, and means associated with said plug for connecting the relatively insulated portions thereof with the respective leads from a source of electricity.

Signed at London, England, this fifth day of December, 1928.

DAVID HODGE.
